LOUIS W. MILLER, OF ROCHESTER, NEW YORK, ASSIGNOR TO J. BURTON WARREN, OF ROCHESTER, NEW YORK.

SIGNAL SYSTEM.

1,278,709.

Specification of Letters Patent. Patented Sept. 10, 1918.

Application filed August 23, 1915. Serial No. 46,778.

To all whom it may concern:

Be it known that I, LOUIS W. MILLER, of Rochester, in the county of Monroe and State of New York, have invented certain 5 new and useful Improvements in Signal Systems; and I do hereby declare the following to be a full, clear, and exact description of the same, reference being had to the accompanying drawings, forming a part of 10 this specification, and to the reference-numerals marked thereon.

My present invention relates to electrical signaling or communicating systems, and has for its particular object to provide a signaling system adapted to be used in cities and municipalities and it is designed to overcome, 15 the objections of previous police signaling systems, particularly with regard to preventing collusion between officers on patrol 20 duty and employees in the police service, station in the main or receiving office of the signaling system. A further object of my invention is to provide a signaling system whereby officers or roundsmen when per- 25 forming their usual duties on the beats ascribed to them, may be signaled or summoned from headquarters or from a precinct station as the occasion demands. A further 30 object of the invention is to provide in a signaling system, means whereby an officer from any one of a number of substations may transmit to headquarters or to a precinct station an emergency call for an ambulance or a patrol wagon and receive forth- 35 with a signal from headquarters indicating that the call has been received and understood. A still further object of the invention is to provide means for accurately recording the exact time when an officer re- 40 ports at the various substations arranged on his beat. To these and other ends the invention consists in certain improvements and combinations of parts all as will be hereinafter more fully described, the novel 45 features being pointed out in the claims at the end of the specification.

In the drawings:

Figure 1 is a diagrammatic view showing the preferred arrangement of service and 50 the apparatus controlled thereby, constituting one embodiment of my invention, and

Fig. 2 is a similar view illustrating the substation apparatus forming a part of the system.

Similar reference numerals throughout 55 the several views indicate the same parts.

In carrying out my invention I provide as shown in Fig. 1, a central office apparatus which is installed at police headquarters or at a police precinct station, to work in conjunction with the substation apparatus shown in Fig. 2. The apparatus shown in Fig. 1 is duplicated for each of the substations of the system, said substations being located at various points throughout the 60 city. The central station and substation are connected by a pair of conductors 4 and 11 normally constituting in conjunction with certain other wires a closed circuit, the current for which is furnished by a battery X. 65

The conductors normally act as a closed telephone circuit, since each substation is provided with a telephone instrument W, while at the central office the main line conductors lead directly to the answering jack 70 K on the switchboard, with which the central operator's cord circuit (not shown) will coöperate in the usual manner. A lamp I in the central office is arranged to be lighted when an officer at the substation removes 75 the telephone receiver from the hook thereby indicating to the central office operator that the patrolman at the substation desires to converse with the central office. The apparatus at the substation, including the telephone W and other devices, which will be hereinafter described, are preferably arranged within a box or inclosure mounted upon a pole or any other suitable form of support. Also mounted upon the support 80 and outside of the box is the signaling apparatus comprising a loud ringing polarized bell U bridged in the main circuit, current for which is preferably furnished by a ring- 85 generator F installed in the central of- 90 fice, and also a visual signal comprising one or more lamps V mounted on supports and adapted to be illuminated by the current from a lighting generator E in the central station controlled preferably by relays D 95 100 and P in a manner which will be hereinafter described. The switchboard at the central office is provided with a ringing key M for sounding the bell U and a lighting switch G for energizing relay D to attract its ar- 105

ature for the purpose of cutting in the generator E when it is desired to light the lamp or lamps V. A switch S' in the box at the

substation is arranged so that when the patrolman opens the door of the box to answer the signal the circuit will be broken thereby releasing the armature of relay D to cut out 5 the generator E and extinguish the light in lamp V. With such apparatus either an audible or visual signal may be displayed at each box or substation as desired, so that a patrolman may be summoned to the sub- 10 station by the central office through the medium of either one of these signals. The switchboard is also provided with signals whereby the central office operator may not only determine whether or not each circuit 15 is in perfect operating condition, but may also be advised when an officer on the beat responds to a signal, and in the event the lights have been displayed at a number of the substations these may be extinguished 20 when the officer called, answers from one of the stations. The emergency signal devices comprise a continuously operating bell or buzzer T' connected across the main line by the relay O, the relay being energized upon 25 operating the switch Q. Also a lamp I in the central station is arranged to be lighted simultaneously with the operation of the switch by the patrolman. The vibrations in the circuit established by the buzzer will 30 also serve to indicate to the central office operator when he plugs into the jack K, the fact that on this circuit the emergency switch at the substation has been operated and that the burning of the light is not due 35 to an accident such as the crossing of circuits, or a broken wire or through any trouble on the line, or by the removal of the telephone receiver from the hook at the sub- 40 station. In this way the central office operator will be able to accurately determine from which substation the call was received so as to obviate dispatching a patrol wagon to the wrong substation. Likewise the continuous ringing of the buzzer T' at the sub- 45 station will indicate to the patrolman that the line is in perfect working condition for displaying the proper emergency signal in the central office.

In police signaling systems it is desirable 50 to keep an accurate record of the time the officers make their reports at the various substations on their beats, so that each and every call transmitted may be recorded, preferably on a time driven ruled record 55 sheet, or chart, and in carrying out this idea I have provided one or more recording relays C adapted to be energized by closing a local circuit or circuits through the relay when either of the switches Q or R are oper- 60 ated for momentarily opening the main line circuit. An armature N carrying a punch or perforator adapted to coöperate with the time driven record sheet is actuated by the relay C when its coil is energized through 65 the closing of the circuit on which the relay

is placed. The chart or record sheet is ar- 70 ranged to be carried by a recording clock N' in position to be perforated by the punch carried on the armature N. It often be- 75 comes necessary for the operator or an offi- 80 cer in the central station to speak with a patrolman on the line about some important matter. In order to accomplish this result I have provided in the central station a "howler" or buzzer L adapted to be con- 85 nected across the line through a cam switch L'. By operating the switch vibrations in the circuit established by the buzzer or "howler" will cause a "howl" or "whistle" 90 in the telephone receiver or receivers at the central office and the substations on the line of the beat traversed by the particular pa- 95 trolman wanted when he pushes the record- 100 ing button R, thus indicating to the patrol- 105 man that the central office desires to get in communication with him and to the central office operator that the patrolman is at the 110 substation.

The operation of the recording button or 115 switch R is similar to that of switch Q ex- 120 cept that the high resistance coil P is short circuited through the telephone receiver in the substation instead of through the relay O. A main line relay A comprises two coils 125 A' and A'' of equal resistance preferably wound upon a single core.

A relay B also comprises two coils wound 130 upon a single core, the resistance of the coils being equal though considerably higher than that of the coils of relay A. Coil B' of re- 135 lay B is arranged in series with the main line and coil B'' is a local winding normally in open circuit and capable of being ener- 140 gized to complete certain circuits for pur- 145 poses which will presently be described, the 150 energizing of the coil being brought about by attracting the armatures of the relays A and B through the opening and closing 155 of the switches Q and R to cut out the re- 160 sistance P of the main line circuit. The 165 main line current traverses the following 170 circuit: beginning at battery X, wire 1, coil 175 B' of relay B, contacts B⁵, B⁶, coil A' of 180 relay A, wire 2, contacts D⁴, D⁵, wire 3, con- 185 tacts M⁴, M⁵, wire 4, wire 5, contacts R⁴, 190 R⁵, wire 6, contacts P⁴, P⁵, wire 7 (also wire 8 and switch S' when door of sub- 195 station box is closed) coil P', wire 9, contacts Q², Q³, wire 10, wire 11, contacts M², M³, wire 12, contacts D⁷, D⁸, wire 13, 200 coil A'' of relay A, and wire 14 back to bat- 205 tery.

The recording relay C as previously stated 210 is arranged in a local circuit and is adapted to be energized when the armature of relay B is deenergized upon the opening of the main line circuit. The relay C comprises a coil 215 C' wound upon a core, one end of the coil being connected to one side of the battery and the other to contact B⁹ of relay B. The 220

armature N on the recording relay C is adapted, when the relay is energized, to be attracted for the purpose of perforating the paper dial or chart on the recording clock 5 N adjacent the relay. The arrangement of the recording clock and the chart to be perforated may be varied according to the number of stations or the conditions of service on the line, the principal object being to 10 provide means for accurately recording the exact time when an officer reports at the various boxes or substations arranged on his beat, there being as will be understood, a recording relay for each of the substations. 15 In despatching the emergency or wagon call from the substation to the central office as previously stated, the switch Q is operated, thereby breaking connection between contacts Q², and Q³ and opening main line 20 circuit thus releasing the armature of relay B, breaking contacts B⁵ and B⁶ and making contact at B³ and B⁴, B⁶ and B⁷, B⁸ and B⁹. When connection is made between contacts B⁶ and B⁷, coils A₁ and A₂ of relay A are 25 again connected with the battery when the switch Q is pushed over and connection made between contacts Q' and Q², at which time high resistance relay P is short circuited through relay O, thus causing an abnormal 30 flow of current through the main line relay A, attracting its armature, breaking connection between contacts A⁸ and A⁹ and making connection between contacts A³ and A⁴, A⁵ and A⁶ and A⁷ and A⁸. When connection is made between contacts A⁷ and A⁸, current will flow from battery through wires 35 1, 17 and 27, contacts A⁷ and A⁸, wire 26, coil B² of relay B and wire 25 back to battery. Coil B² of relay B being thus energized the armature of the relay will again 40 be attracted and connection broken between contacts B⁸ and B⁹, thereby deenergizing recording relay C and making connection between contacts B⁵ and B⁶ and restoring the 45 main line circuit through coil B' of relay B. The armature of relay A still being attracted by the abnormal flow of current through the main line, current for lighting the signal lamp I in the central station will 50 flow from battery through wire 1, coil B' of relay B, contacts B⁵ and B⁶, wires 23 and 22, contacts A⁵ and A⁶, wire 16, contacts A² and A⁴, wire 54, contacts K² and K⁴, wire 55, lamp I and wires 56 and 20 to battery. 55 At the time the emergency call is despatched by means of the switch Q, the relay O having a coil O' wound upon a core is adapted to be connected across the main line, with the operation of the switch to connect the 60 contacts Q' and Q². When this is done relay O becomes energized, current flowing through main conductor 4, wire 5, contacts R⁴ and R⁵, wires 6 and 30, coil O', wire 31, contacts Q' and Q² and wire 10 to main line 65 conductor 11. Should connection be broken between contacts Q' and Q², relay O will continue to be energized, until the battery is cut off at the switchboard by pressing the ringing key M. When connection is broken between contacts Q' and Q² the current from 70 battery X passing through main line conductor 4 will continue through wire 5, contacts R⁴ and R⁵, wires 6 and 30, coil O' of relay O, wire 32, contacts O³ and O⁴, wires 28 and 10 to main line conductor 11. At the 75 same time current for the buzzer T' passing through main line conductor 4 will flow through wire 5, wire 29, buzzer T', wire 33, contacts O² and O³, and wires 28 and 10 to main line conductor 11. The buzzer will 80 continue in operation until the ringing key M in the central office is depressed by the central office operator. 85 As previously stated the switchboard at the central office is provided with the ringing key M for the purpose of sounding the polarized bell U at the substation as a signal to the patrolman making his rounds that the central office wishes to communicate with him. The ordinary main line current furnished by the battery X and normally passing through the switch M will not cause the polarized bell U to be sounded and therefore 90 as a means for ringing the bell I have provided the ringing generator F, as previously 95 stated, which is preferably an alternating current generator. The coils of the polarized bell U are connected to the conductors 4 and 11 by wires 33' and 34 and in one of these wires is inserted a condenser U' for preventing the flow of the main line current through this branch circuit. When the central office operator desires to signal a patrolman on the line by ringing the bell U at the substation he operates the switch M to make connection between contacts M' and M² and M³ and M⁴, thereby connecting the main line conductors 4 and 11 with wires 35 and 36 leading to the generator F from which the necessary current is received for sounding 100 the bell. At the same time when ringing key M is depressed connection is made between contacts M⁷ and M⁸ thus completing circuit from battery through wire 37, contacts M⁷ and M⁸, wire 38, local coil B² of relay B, 115 through wire 25 back to battery thereby holding armature of relay B attracted while connection is broken between contacts M² and M³ and M⁴ and M⁵. As soon as the officer has answered the bell at the substation 120 the ringing generator F is cut out and the main line is thereby automatically restored to normal. 125 As previously stated a lighting generator E is located in the central station for the purpose of furnishing current with which to light the lamp or lamps V in the substation. The generator circuit is controlled by the switch G and relay D in the central office and the high resistance relay P in the sub- 130

station, the armature of which is not attracted by the current from battery X normally passing through the main line and the relay. When the central office operator 5 sires, by the use of the lamps V, to signal a patrolman on the line making the rounds of the substations on his beat he signals the substations nearest the last from which the officer reported in the direction in which the 10 officer is traveling. This is done by closing the switch G in the central office, thus making connection between contacts B' and G² thereby causing current from battery to flow through wires 1, 17 and 27, contacts A⁸ and 15 A⁹, wires 40 and 41, contacts G' and G², wire 42, coil D' of relay D and wire 39 back to battery. In this way local coil D' of relay D is energized thereby attracting the armature of relay D, breaking connection between 20 contacts D⁴ and D⁵ and D⁷ and D⁸ and making connection between contacts D³ and D⁴, D⁶ and D⁷ and D⁹, D¹⁰ and D¹¹, which as will be understood cuts out the main line circuit through coils A' and A² of relay A 25 and coil B' of relay B. At the same time coil B² is energized to hold the armature of relay B attracted, current flowing from battery through wires 37 and 43, contacts D¹⁰ and D¹¹, wires 44 and 38, coil B² of relay B 30 and wire 25 back to battery. Circuit is also completed from battery through wires 37 and 43, contacts D⁹, D¹⁰ and D¹¹, wires 45 and 19, red lamp J and wire 20 back to battery. When connection is made between 35 contacts D³ and D⁴ and D⁶ and D⁷ the lighting circuit is then established from one pole of generator E through wire 46, coil D² of relay D, wire 47, contacts D⁶ and D⁷, wire 12, contacts M² and M³, wires 11 and 10, contacts Q², and Q³, wire 9, coil P', wire 8, contacts S² and S³ of switch S', wires 48 and 6, contacts R⁴ and R⁵, wires 5 and 4, contacts M⁴ and M⁵, wire 3, contacts D³ and D⁴, wire 49, ammeter H and wire 50 back to generator E. As long as the red lamp J remains 45 lighted the central office operator will know that the signal lamp at the substation is burning and that the generator circuit in which the lamp is placed is in working condition. 50

When the telephone receiver is off the hook in the substation and armature of relay A is attracted, switch G cannot be operated to cut in generator E. As stated before, the 55 battery current flowing through main line to relay P is not sufficient to attract the armature of the relay, due to the high resistance of the coil P' but when a current of a higher voltage from the generator E is 60 passed through the relay in the manner just described, its armature will be attracted, thus making connection between contacts P² and P³ and completing circuit through wire 8, wire 51, lamp V, wire 52, contacts P² and 65 P³, wire 53 and back to wire 9, thereby light-

ing the lamp V as a signal to the patrolman wanted by the central office. As soon as the patrolman opens the door of the box at the substation to respond to the call or signal from the central office, connection between 70 contacts S² and S³ is broken thereby opening the main circuit, whereupon the armature of relay D is released and connection broken between contacts D³ and D⁴ and D⁶ and D⁷, thus cutting out the generator circuit, which 75 cannot be restored except by closing the switch G. At the same time the main line circuit is restored through contacts D⁷ and D⁸ of relay D and relays A and B.

A description of the arrangement of the 80 parts of the recording relay C has been given in connection with the operation of the emergency switch Q and as the arrangement is the same in the case of the operation of the recording switch R, it will only be necessary to outline the circuit necessary to complete the transmission of current through the recording relay when the switch R is operated. The principal difference in the operation of the switch Q and the recording 85 switch R is that in the case of the former the high resistance relay P is short circuited through the relay O, while in the case of the latter the high resistance relay is short circuited through the telephone receiver Z in 90 the substation. When the patrolman operates the switch R to produce upon the record sheet of the recording clock a record of the time of his report at the substation, the main line circuit is opened, thereby releasing the 95 armature of relay B and making connection between contacts B³ and B⁴, B⁶ and B⁷, and B⁸ and B⁹.

The armature of relay B being released and connection made between contacts B⁸ and B⁹ the recording relay C will be energized, current passing from battery through wires 1, 17, contacts B⁷ and B⁶, wires 23 and 22, contacts A⁶ and A⁵, wire 16, contacts A⁴ and A³, wire 15, contacts B⁸ and B⁹ and coil 105 C' of relay C and back to battery. When the armature of relay B falls away connection is also made between contacts B⁶ and B⁷, thereby again connecting coil A' of relay A with the battery so that when the switch 110 R is pushed over and connection is made between contacts R' and R² and R³ and R⁴ high resistance relay P is short circuited through wires 57 and 58, receiver Z, wires 59 and 60, contacts R² and R⁴, wire 5 and 115 back to main line, thus causing an abnormal flow of current through main line relay A, attracting its armature breaking connection between A⁸ and A⁹ and making connection between contacts A³ and A⁴, A⁵ and A⁶ and 120 A⁷ and A⁸. When connection is made between contacts A⁷ and A⁸ current will flow from battery through wires 1, 17 and 27, contacts A⁷ and A⁸, wire 26, coil B² of relay B and wire 25 back to battery. Coil 125

B² of relay B being thus energized, the armature of the relay will again be attracted and connection broken between contacts B⁸ and B⁹, thereby deenergizing relay 5 C and making connection between contacts B⁵ and B⁶ and restoring the main line circuit through coil B' of relay B. The armature of relay A still remaining attracted by the abnormal flow of current through the 10 main line, current for lighting the signal lamp I in the central office will flow from battery through wire 1, coil B' of relay B, contacts B⁵ and B⁶, wires 23 and 22, contacts A⁵ and A⁶, wire 16, contacts A³ and A⁴, 15 wire 54, contacts K³ and K⁴, wire 55, lamp I and wires 56 and 20 back to battery. As soon as the push button R is released connection is again made between contacts A⁸ and A⁹ and the main line is consequently 20 restored to normal.

In cases where patrolmen at the substation wish to get in touch with the central office, communication may be had, as previously stated, through the telephone set W 25 which comprises the transmitter W' and the receiver Z on the hook Y and contacts Y' and Y² and Y³ and Y⁴ for making connection with the main line circuit when the receiver is removed from its hook. When the 30 receiver is removed current will travel through main line wire 4, wire 5, switch R, wires 6, 30 and 61, contacts Y' and Y², transmitter W', wire 58, receiver Z, wire 59, contacts Y³ and Y⁴, wires 62 and 9, 35 switch Q and wire 10 to main line wire 11. When connection is made between contacts Y' and Y² and Y³ and Y⁴ high resistance relay P is thereby short circuited, thus causing an abnormal flow of current through 40 the main line circuit, attracting the armature of relay A and making connection between contacts A³ and A⁴, A⁵ and A⁶, and A⁷ and A⁸. Current then flows from battery through wires 1 and 17, contacts 45 B⁷ and B⁶, wires 23 and 22, contacts A⁶ and A⁵, wire 16, contacts A⁴ and A³, wire 54, contacts K³ and K⁴, wire 55, lamp I and wires 56 and 20 back to battery, the lighting of the lamp I being a signal to the central 50 office operator that a patrolman on the line wishes to talk with the central office. When connection is made between contact A⁷ and A⁸ coil B' of relay B is short circuited through coil B², thereby energizing relay 55 B and holding its armature attracted. As soon as the receiver Z is placed on the hook Y in the substation connection is broken between contacts Y' and Y² and Y³ and Y⁴, thus restoring the main line circuit to normal, causing relay A to release its armature to allow connection to again be made between contacts A⁸ and A⁹.

As stated above, it often becomes necessary for the operator or an officer in the central station to talk with a patrolman on the 60

line at one of the substations and to communicate to the patrolman a signal indicating that it is desired to have him get in telephonic communication with the central office. The buzzer or "howler" L which has 70 been provided in the central office for this purpose comprises a normally open switch L' having contact members L² and L³ connected by wires 63 and 64 arranged to connect with branch wires 65 and 66 which 75 lead to the contacts K' and K² and also main line wires 13 and 2. Contact members L⁴ and L⁵ are connected to wires 67 and 68 respectively, which connect through condensers 69 and 70 with the secondary winding 80 71 of an induction coil, the primary winding of which is indicated at 72. A battery S is provided for energizing the primary winding, one end of which is connected with the contact member L⁷ and the 85 other end to a vibrator T in the normally open circuit of the battery S. One side of the battery is connected with the contact L⁶ by the wire 74 and the other side to the vibrator by the wire 75. Whenever the central 90 office desires to notify the patrolman making the rounds on his beat that he is wanted on the telephone, the switch L' of the buzzer or "howler" L is closed, thereby connecting the "howler" with the main 95 line through the engagement of contacts L² and L⁴, L³ and L⁵ and L⁶ and L⁷. The switch is allowed to remain closed until the patrolman reaches one of the substations on his beat and operates the switch R to record, 100 at the central office, the time of his report at said station. As soon as he operates the switch R the high resistance relay P is short circuited through the telephone receiver Z thereby causing an abnormal flow of current 105 through the main line, thus causing the buzzer L to produce a "howl" or "whistle" in the receiver at the substation, which will notify the patrolman that he is wanted on the phone by the central office. The removal 110 of the telephone receiver by the patrolman will cause the lamp I to be lighted in the central office, which will indicate to the central office operator that the patrolman is on the line. As soon as the central office operator plugs into the jack K the "whistle" will also be audible in the central office telephone receiver and will indicate to the operator that the patrolman at the substation is on the phone in answer to the signal 115 produced by the buzzer L. The switch L' of the buzzer is then opened and the "whistle" in the telephone receiver is thereby discontinued.

In the event that there are a number of 120 the lamps V on the substation circuit controlled by the generator E, the ammeter H, serving to show the amount of current passing through the circuit, will indicate to the central office operator whether or not any 125 130

of the lamps in the circuit have become extinguished. The central office signal lamp I, which is preferably arranged to furnish a white light, may be tested from time to time by plugging into the jack switch K. When this is done connection is made between contacts K⁴ and K⁵, current then flowing from battery through wires 1, 17 and 27, contacts A⁸ and A⁹, wires 40 and 73, contacts 10 K⁴ and K⁵, wire 55, lamp I and wires 56 and 20 back to battery.

While I have preferably described my signaling system as being operated by the use of a direct current it will be seen that 15 the apparatus may also readily be used in connection with an alternating current.

I claim as my invention:

1. In a signal system, the combination with a central station, a substation and a 20 normally closed line circuit connecting them, a resistance in the line circuit, an emergency signal at the central station, an electromagnet in the main circuit normally maintaining the signal in an inoperative condition and adapted to be operated by short 25 circuiting the resistance, a line relay, a recording mechanism, a relay for controlling the same provided with a circuit adapted to be closed by the line relay when the main 30 circuit is opened, and opened by the line relay when the resistance is short circuited, a normally open branch circuit connected to the line at the substation and a switch for opening the main circuit and closing the 35 branch circuit to short circuit the resistance.

2. In a signal system, the combination with a central station, a substation and a normally closed line circuit connecting them, a resistance in the line circuit, an emergency 40 signal at the central station, an electromagnet in the main circuit normally maintaining the signal in an inoperative condition and adapted to be actuated for operating the same by short circuiting the resistance, a 45 normally open branch circuit connected to the line, a switch in the main circuit at the substation adapted when operated to open the main circuit and to short circuit the resistance by closing the branch circuit, a 50 recording mechanism, a relay in a normally open circuit for controlling the same, a second relay adapted upon the operation of the switch opening the main circuit to cause said first mentioned relay to be energized 55 and upon short circuiting the resistance to cause the relay to be deenergized.

3. In a signal system, the combination with a central station, a substation and a normally closed line circuit connecting them, 60 an emergency signal at the central station, an electromagnet in the line circuit having an armature normally maintaining the emergency signal in an inoperative condition, a double wound relay having one of its 65 coils normally in the main circuit, arranged

to be deenergized upon the opening of the main circuit, and the other coil in an open circuit and arranged to be energized upon the attraction of said armature, a recording mechanism, a relay controlling it having a 70 circuit adapted to be closed between the period of deenergization of the first mentioned relay coil and the energization of the second mentioned relay coil, a resistance in the main circuit and a switch in the substation adapted when operated to open the main circuit and to short circuit the resistance the opening of the circuit causing the deenergization of the first mentioned relay coil and the short circuiting of the resistance causing the electromagnet to attract said armature for the purpose of operating the emergency signal and energizing said second mentioned relay coil.

4. In a signal system, the combination with a central station, a substation and a normally closed line circuit connecting them, an emergency signal at the central station, an electromagnet in the line circuit having an armature normally maintaining the 90 emergency signal in an inoperative condition, a double wound relay having one of its coils normally in the main circuit, arranged to be deenergized upon the opening of the main circuit, and the other coil in an 95 open circuit and arranged to be energized upon the attraction of said armature, a recording mechanism, a relay controlling it having a circuit adapted to be closed between the period of deenergization of the 100 first mentioned relay coil and the energization of the second mentioned relay coil, a normally open branch circuit connected to the line at the substation and provided with a sounder, a resistance in the main circuit, 105 and a switch at the substation adapted when operated to open the main circuit and to short circuit the resistance by closing said branch circuit, the short circuiting of the 110 resistance causing the electromagnet to attract said armature for the purpose of operating the emergency signal.

5. In a signal system, the combination with a central station, a substation and a closed line circuit connecting them, a normally inoperative signal at the substation, of a source of energy at the central station, mechanism at the substation adapted upon connection of the source of energy with the line circuit to operate said signal, a double 115 wound line controlling relay at the central station having one of its coils in the line circuit and the other normally in an open branch circuit, a switch at the central station and means controlled by the switch for 120 closing the branch circuit and connecting the source of energy with the line circuit.

6. In a signal system, the combination with a central station, a substation and a closed line circuit connecting them, a nor- 125

- 5 mally inoperative signal at the substation, a source of energy at the central station, of mechanism at the substation adapted upon connection of the source of energy, 5 with the line circuit to operate said signal, line controlling mechanism at the central station having an open circuit, a switch at the central station and means controlled by the switch for closing the open circuit and 10 arranged to connect the source of energy with the line circuit.
6. In a signal system, the combination with a central station, a substation and a closed line circuit connecting them, a normally inoperative signal at the substation, a source of energy at the central station, of mechanism at the substation adapted upon connection of the source of energy with the line circuit to operate said signal, line controlling mechanism at the central station having an open circuit, a switch at the central station, means controlled by the switch for closing the open circuit and connecting the source of energy with the line circuit 25 and means at the substation for disconnecting the source of energy and causing the line controlling mechanism to restore the line circuit to normal.
7. In a signal system, the combination with a central station, a substation and a normally closed line circuit connecting them, a resistance in the line circuit, an emergency signal at the central station, an electromagnet in the line circuit normally maintaining the emergency signal in an inoperative condition and capable of being operated to actuate the signal, a double wound relay having one of its coils normally in the main circuit, arranged to be deenergized upon the opening of the main circuit, and the other coil in an open circuit and arranged to be energized upon the operation of the electromagnet, a recording mechanism, a relay controlling it having a circuit adapted to be closed only between the period of deenergization of the first mentioned relay coil and the energization of the second mentioned relay coil, a sounder positioned in an open branch circuit at the 50 substation adapted to operate upon closing the branch circuit to short circuit the resistance and arranged to be rendered inoperative only from the central station, and a switch at the substation adapted to open the main and close the branch circuit to short circuit the resistance for the purpose of causing the operation of the electromagnet.
8. In a signal system, the combination with a central station, a substation and a normally closed line circuit connecting them, a resistance in the line circuit, an emergency signal at the central station, an electromagnet in the line circuit normally maintaining the signal in an inoperative condition and adapted to be operated by short circuiting the resistance, a line relay, a recording mechanism, a relay for controlling the same provided with a circuit adapted to be closed by the line relay when the 70 resistance is short circuited, a normally open branch circuit connected to the line at the substation, a switch for opening the main circuit and closing the branch circuit to short circuit the resistance and means at the central station for rendering the signal inoperative and restoring the line circuit to normal.
9. In a composite telephone and signal system, the combination with a central station, a substation and a normally closed line circuit connecting them, a resistance in the line circuit, a signal at the central station, mechanism in the line circuit normally maintaining the signal in an inoperative 80 condition and adapted to operate the same upon short circuiting the resistance, a plurality of signaling members at the substation each of which is adapted when operated to open the line circuit and short circuit the resistance, and signal answering mechanism at the central station common to all of said signaling members, one of said members being provided with means for producing through the answering mechanism a signal at the central station when said member is operated.
10. In a composite telephone and signal system, the combination with a central station, a substation and a normally closed line circuit connecting them, a resistance in the line circuit, a signal at the central station, mechanism in the line circuit normally maintaining the signal in an inoperative 85 condition and adapted to operate the same upon short circuiting the resistance, a plurality of signaling members at the substation each of which is adapted when operated to open the line circuit and short circuit the resistance, and signal answering mechanism at the central station common to all of said signaling members, one of said members being provided with means for producing through the answering mechanism a signal at the central station when said member is operated.
11. In a composite telephone and signal system, the combination with a central station, a substation and a normally closed line circuit connecting them, a resistance in the line circuit, a signal at the central station, mechanism in the line circuit normally maintaining the signal in an inoperative 90 condition and adapted to operate the same upon short circuiting the resistance, a recording mechanism, a relay for operating it having a normally open branch circuit, means for closing and opening the branch circuit upon the opening and closing of the line circuit, a plurality of signaling members at the substation each of which is adapted when operated to open and close the line circuit to short circuit the resistance, and signal answering mechanism at the central station common to all of said signaling members, one of said members being provided with means for producing through the answering mechanism a signal at the central station when said member is operated.
12. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 100
13. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 105
14. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 110
15. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 115
16. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 120
17. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 125
18. In a signal system, the combination with a central station, a substation and a closed line circuit connecting them, a normally inoperative signal at the substation, a generator normally in open circuit, a magnet at the substation adapted upon connection of the generator with the line circuit to operate said signal, a relay at the central station normally in the line circuit, an open 130

branch circuit leading from the line circuit to the relay, means for simultaneously causing the relay to open the line circuit to connect the generator therewith and to close the branch circuit through the relay, and a signal at the central station in the branch circuit adapted to be operated upon connection of the generator and line circuit and to be rendered inoperative upon open-

ing the generator circuit, said signal being 10 for the purpose of indicating whether or not the generator circuit is in operating condition.
